UNITED STATES PATENT OFFICE.

JACOB HIBBARD, OF HERMITAGE, NEW YORK.

FEED-WATER APPARATUS FOR STEAM-BOILERS.

Specification of Letters Patent No. 26,847, dated January 17, 1860.

To all whom it may concern:

Be it known that I, JACOB HIBBARD, of Hermitage, in the county of Wyoming and State of New York, have invented a new and useful Improvement in Modes of Supplying 5 Boilers with Water; and I do hereby declare that the following is a full and exact description thereof, reference being had to the accompanying drawings, and to the letters of 10 reference marked thereon, making part of this specification.

The nature of my invention relates to the construction and mode of operation of feeding cylinders to supply steam boilers substantially as hereinafter represented and 15 described.

With reference to the accompanying drawings, Figure 1, is a plan, Fig. 2, an elevation, Fig. 3, a sectional elevation, and Fig. 4, a 20 sectional plan, illustrating my improvement.

A, is a tank or reservoir, and E, the boiler to be supplied from said tank. Between the two is arranged the casting B.

Within the casting B, is closely fitted so 25 as to be free to rotate the cylinder C. Projecting upward from the cylinder is the shank C¹ around which is fitted the bearing piece D, which serves as a bearing for the shank C¹ and also keeps the cylinder in its 30 place in the casting B. This bearing piece D, is secured by the two bolts A. Cylinder C, is provided with a chamber C². This chamber opens through the side of the cylinder in one place only. In the casting B, is 35 a passage B¹ leading from the cylinder's surface to the interior of the boiler, E. This passage B¹ corresponds in size and shape to the opening of the chamber C² through 40 the side of cylinder C, and opens into the boiler E, at a point lower than that where it leaves the surface of the cylinder C. In the casting B, opposite the passage B¹ is the passage B² of similar size and shape and leading 45 from the surface of the cylinder to the water tank A. The water tank should in all cases have its bottom at an elevation as high at least as the bottom of the chamber C² in the cylinder. The set screw b, forms a pivot on 50 which the lower end of the cylinder turns so as in some measure to relieve it from the friction upon its surface and lower end to which it would otherwise be subject. A gear F, is attached to the shank C¹ into 55 which plays the pinion G. This pinion G, is

attached to a shaft having its bearing in stand H. On this shaft is the pulley I, which may be driven by a belt passing from any suitable revolving shaft connected with the engine or otherwise, provided a suitable speed with certain power is secured. The cylinder C, thus being made to revolve continuously should also revolve with a speed somewhat exceeding in the number of revolutions per minute the number of times which the chamber C² would require to be filled and emptied into the boiler to keep the water therein at the proper height. The upper side of the opening of the passage B¹ into the boiler should correspond to the required height of water in the boiler in all cases, as indicated by the line E¹ in Fig. 3. The parts may be made of cast iron or other material suited to this class of work.

Having thus set forth the construction of 75 my improvement I will proceed to describe the operation.

The boiler having been filled, the steam 80 got up and the engine set in motion thereby causing the cylinder to revolve as described so soon as the opening into chamber C² connects with the passage B² from the water tank, the water from passage B² begins to fill it and before the connection ceases by the opening of chamber C² getting 85 past the passage B² the chamber C² is filled with water and immediately by the continued revolution of the cylinder the opening connects in turn with passage B¹, when if the water in the boiler is below line E¹, 90 the passage B will be full of steam which at once rushes into and fills chamber C², the steam being lighter than the water, the water must fall down into the boiler the cylinder passing on in its revolution brings 95 the opening chamber C² again in connection with passage B² and so exposes the steam with which it is filled to contact with the water thereby instantly condensing it or allowing it to pass up through the water so 100 the water again fills chamber C² and is deposited in the boiler when the connection again occurs with B¹ as before. This process goes on till the water attains the level E¹ coinciding with the top of the opening of B¹ 105 into the boiler after which the steam cannot enter passage B¹ so then its pressure upon the water keeps it up in contact with cylinder C, so preventing any more water passing into the boiler until the water in the 110

boiler falls again below line E¹ as described. Thus the water is kept at the proper height and the evils and dangers consequent upon too much or too little water in the boiler 5 effectually avoided. While the water remains above line E¹ the water in the boiler is forced up by the pressure of steam against the cylinder C, and there is consequently an alternate mixing of the hot water in the 10 boiler with the water in the chamber C² and of that with the water in passage B² this serves to warm the water in the tank before entering the boiler.

Having described the construction and 15 operation of my invention what I claim

therein as new and desire to secure by Letters Patent is as follows.

I claim the arrangement of the rotating feed plug C, receiving its water on one side, and discharging it into the boiler on the 20 other; the operation being performed by the continuous rotation of the plug, all in the manner and for the purpose substantially as set forth.

In testimony of which invention I have 25 hereunto set my hand.

JACOB HIBBARD.
